UNITED STATES PATENT OFFICE.

ESKIL V. PALMQUIST, OF HALLANDALE, AND HENRY G. LUNDQUIST, OF SEMINOLE COUNTY, FLORIDA.

AIR-BRAKE STOP.

1,230,767.

Specification of Letters Patent. Patented June 19, 1917.

Application filed May 8, 1915. Serial No. 26,871.

To all whom it may concern:

Be it known that we, ESKIL V. PALMQUIST, of Hallandale, in the county of Dade and State of Florida, and HENRY G. LUNDQUIST, of Seminole county, in the State of Florida, citizens of the United States, have invented certain new and useful Improvements in Air-Brake Stops, of which the following is a specification, reference being had 10 therein to the accompanying drawing.

This invention relates to an automatic brake throwing mechanism to be used upon railroad trains and the like, and has for its object the production of a simple and efficient means which may be directly attached to the train pipe for causing the setting of the brakes in coöperation with the ordinary brake throwing mechanism.

Another object of this invention is the 20 production of a simple and efficient valve means coöperating with the train pipe for the purpose of producing an exhaust when the train passes a predetermined point or track instrument.

A still further object of this invention is 25 the production of a simple and efficient track instrument which may be employed in connection with the brake throwing mechanism.

With these and other objects in view this 30 invention consists of certain novel combinations, constructions, and arrangements of parts as will be hereinafter fully described and claimed.

In the accompanying drawings:—

Figure 1 is a side elevation of the rear portion of the tender of the locomotive showing the valve mechanism carried thereby.

Fig. 2 is a top plan view of the track 40 mechanism employed in connection with the present invention, the operating valve and train pipe being shown in combination therewith.

Fig. 3 is a section taken on line 3—3, of 45 Fig. 2.

Fig. 4 is a vertical section through the valve mechanism.

Fig. 5 is a detail perspective view of the lower section of the valve casing.

Fig. 6 is a transverse sectional view 50 through the valve taken on line 6—6, of Fig. 4.

Fig. 7 is a perspective view of the bracket employed in connection with supporting the 55 valve.

Fig. 8 is a transverse sectional view

through the track instrument used in connection with the present device and adapted to be supported to the side of the rail.

Fig. 9 is a top plan view of an embodiment of the present invention showing the operation of the track instrument from a distant point.

By referring to the drawings it will be seen that 1 designates the tender or other portion of a train upon which the device may be employed. A bracket 2 for supporting the valve casing 3 is secured to the truck 4 by having its parallel jaws 5 fitting over the journal portion of the truck 4 as illustrated in Figs. 1 and 4 of the drawings. The bracket 2 is provided with a pair of spaced collars 6, which collars have their outwardly extending adjoining ends 7 securely fastened together by means of bolts 8. 75

A valve casing 9 is supported within the ring 6, and this casing 9 is provided with an annular flange 10 around the bottom thereof which is provided with a plurality of laterally extending ears 11. These ears 11 support or engage the ears 12 carried by the tapering cap 13 as clearly illustrated in Figs. 4 and 5 of the drawings. The tapering cap 13 is provided with a pocket 14 formed therein, which pocket 14 carries a 80 vertically movable valve 15 having a valve head 16 formed upon the top thereof for normally closing the passage through the valve seat 17 formed within the cap 13. This structure is clearly illustrated in Figs. 90 4 and 5 of the drawings. The valve stem 15 is provided with an enlarged head 18 and a coil spring 19 is carried thereby and engages the head 15, and also engages the lower end of the cap 13 as clearly illustrated in Fig. 4 95 of the drawings. A discharge port 20 is formed integral with the cap 13 and is provided with a discharge aperture 21 formed therein communicating with the pocket 14.

As clearly illustrated in Fig. 2 of the 100 drawings the train pipe 22 is carried in the usual manner upon the lower face of the train or car, and a supply pipe or communicating pipe 23 is connected thereto by means of an elbow or T joint 25. The pipe 23 is 105 also connected to the elbow 25, which elbow is in turn connected to the body of the valve 9 as clearly illustrated in Fig. 4.

As illustrated in Fig. 2 of the drawings and also in Fig. 1 it will be seen that a supporting plate 26 is positioned to one side of the rails, and to these supporting plates 26 110

are secured the tripping plates 27 by means of the flanges 28 as clearly illustrated in Fig. 8 of the drawings. Stop brackets 29 are secured to the plates 26 and are provided with upwardly extending portions which limit the upward movement of the plates 27 as the same are swung upwardly by means of the crank mechanism 30. This crank mechanism 30 extends transversely of the track and under the rails 31 thereof as clearly illustrated in Fig. 2 and is provided with a plurality of crank portions 32 which are adapted to fit under the tripping plate 27 and throw the same at right angles to the plate 26 or to the position shown in dotted lines in Fig. 8 of the drawings. It should be understood that the crank portions 32 project through the space 33 formed between the plates 26. One end of the crank shaft carries a beveled gear 34, which beveled gear 34 meshes with a beveled gear 35 carried by the operating shaft 36, and this operating shaft 36 carries a crank handle 37 for the purpose of allowing the shaft 36 to be rotated for rotating the shaft 30.

From the foregoing description it will be seen that a very simple and efficient means has been produced for the purpose of setting the tripping plate 27.

In Fig. 9 there is shown an embodiment of the invention wherein the crank shaft 30' is connected by means of a link 38 to an operating cable 39 to facilitate the operation of the tripping plate 27' from a distance. A coil spring 40 is connected to the base plate 41 and also to the under face or inner face of the tripping plate 27 so as to normally draw the tripping plate 27 to an inoperative position as soon as the crank portion 32' has been thrown flat upon the supporting or base plate 41.

By carefully considering Fig. 1 it will be seen that the tripping plate 27 is beveled or tapers at each end as indicated by the nu-

meral 27' for the purpose of permitting the lower end of the plunger 15 to easily slide thereon.

From the foregoing description it will be seen that a very simple and efficient tripping mechanism has been produced for the purpose of setting the air brakes upon a train, providing the train should pass beyond a predetermined point, in view of the fact that the plunger 15 will engage the tripping plate carried to the side of the track and in this manner open the valve 16 and permit the escapement of compressed air for the purpose of applying the air brakes in the usual manner.

Having thus described the invention what is claimed as new, is:—

In a device of the class described, the combination of a bracket, said bracket comprising a body, spaced jaws extending from said body, said jaws being adapted to embrace a truck bolster so as to permit means to pass therethrough for supporting said bracket, a valve member, collars formed upon said body in spaced relation with respect to each other, said collars embracing said valve member, said collars having outwardly extending adjoining ends, said ends engaging each other, and means for holding the same together, whereby said collars will positively hold said valve member.

In testimony whereof I hereunto affix my signature in presence of two witnesses.

ESKIL V. PALMQUIST.
